UNITED STATES PATENT OFFICE.

WILLIAM R. BOOTH, OF GRAVETTE, ARKANSAS.

PORTABLE DRILLING-STAND.

1,111,944.

Specification of Letters Patent. Patented Sept. 29, 1914.

Application filed March 28, 1914. Serial No. 828,026.

To all whom it may concern:

Be it known that I, WILLIAM R. BOOTH, a citizen of the United States, residing at Gravette, in the county of Benton and State 5 of Arkansas, have invented certain new and useful Improvements in Portable Drilling-Stands, of which the following is a specification, reference being had to the accompanying drawings.

10 This invention relates to drills, and more particularly to a drill which is supported in a portable stand.

An object of this invention is the provision of a drilling stand of this character 15 which comprises a frame upon which a supporting table is adjustably mounted, above which a feeder bar is pivotally mounted, the treadle being adapted for engagement with the feeder bar, and a drill connected to the 20 base of the frame to move the feeder bar downwardly to force the drill into the work supported upon the table.

A further object of this invention is the provision of novel means for detachably supporting a wheel or similar device which it is 25 desired to drill, in the frame below the feeder bar.

With these and other objects in view, my invention consists in the novel construction, 30 combination, and arrangement of parts to be hereinafter more fully described, claimed, and illustrated in the accompanying drawing, in which,

Figure 1 is a front elevation of my device; 35 Fig. 2 is a side elevation thereof; Fig. 3 is a sectional view on the line 3—3 of Fig. 1; and Fig. 4 is a sectional view on the line 4—4 of Fig. 1.

Referring more particularly to the drawing, the numeral 1 designates a pair of spaced base bars in which standards 2 and 3 are mounted, the standards being connected at their upper and lower ends by brace rods 4 and 5, respectively. A bracket 45 is adjustably connected to the standard 3 adjacent its lower end, the bracket comprising a horizontally disposed rod 6, which is connected to the standard by the U-shaped plate 7, and a U-shaped brace plate 8, the 50 intermediate portion of which is connected to the standard below the plate 7, and the opposite ends of which are connected to the opposite side faces of the rod 6 adjacent its free end. The standard 3 is formed with a 55 plurality of bolt openings 9 in which the bolts 10 and 11 which engage the plate 7

and the brace 8, respectively, are mounted, whereby the bracket is vertically adjustable with relation to the frame. A work supporting table 12 is mounted on the free end 60 of the bar 6 to support the work which it is desired to drill.

A U-shaped supporting plate 13 is pivotally connected to the standard 3 above the plate 7 and connected to the opposite ends 65 of the plate 13 is one end of a feeder bar 14, the opposite end of the bar 14 having a pair of guide plates 15 connected on opposite sides thereof, the guide plates projecting beyond the free end of the bar 14 for 70 engagement with the opposite side faces of the standard 2 to guide the bar in its vertical movement in the frame. A socket 16 is formed in the lower face of the bar 14 intermediate of its ends, and suitably mounted 75 in the socket is the upper end of a brace 17, which is formed with a crank 18 intermediate of its ends, and mounted in the lower end of the brace is the bit or drill 19 for 80 drilling the work supported upon the table.

To move the feeder bar 14 vertically within the frame, a treadle 20 is pivotally connected at one end to one of the base members 1, and a connecting rod 21 is connected 85 at its lower end to the free end of the treadle 20 and at its upper end to the free end of the bar 14, so that upon pressure upon the treadle 20, the bar 13 is moved downwardly to force the drill 19 into engagement with 90 the work supported upon the table 12. The lower brace rod 5 is preferably sectional, the rod consisting of a pair of tubular sections 22 which are mounted at one end in the standards 2 and 3, the inner ends of the tubular sections 22 being spaced from each other for the reception of the opposite ends 95 of an intermediate rod 23, the rod 23 being normally maintained in engagement with the opposing ends of the sections 22 by set screws 24 which are disposed through the opposing ends of the tubular sections and into engagement with the opposite ends of the intermediate section 23.

It will be seen that when it is desired to 105 drill a wheel or other similar device (not shown), the set screws 24 are loosened so that the rod 23 may be moved to one side to allow the wheel to be placed between the opposing ends of the sections 22, whereupon 110 the opposite ends of the rod 23 may again be secured in the opposing ends of the sec-

tions 22 so that the rod forms a support for the wheel.

In the practical use of my device, the work to be drilled is placed upon the table 12, whereupon the treadle bar is depressed by the foot of the operator to bring the drill 19 into engagement with the work, so that upon turning of the crank 18 of the brace, the drill bores into the work and is forced into the same by the continued pressure upon the treadle bar 20. When it is desired to bore holes into the rim of a wheel or the like, the bracket may be removed from the standard 3 and the wheel supported upon the rod 23 in the manner heretofore described, so that the rim of the wheel is disposed in the path of the drill 19 so that the same may be moved downwardly into engagement with the rim upon depression of the treadle 20 in the usual manner.

Having thus fully described my invention, what I desire to secure and claim by Letters Patent, is:—

1. A device of the character described comprising a frame including a pair of spaced standards, a drill supporting bar pivotally connected at one end to one of said standards adjacent its upper end, a pair of guide plates connected to the opposite sides of said bar at its opposite end and projecting longitudinally therefrom, the projecting portions of said plates being engaged

against the opposite side faces of the other of said standards, a work supporting member connected to one of said standards below said bar, a depending drill carried by said bar, and means for moving said bar downwardly to force the drill into engagement with the work upon the supporting member. 35 40

2. A device of the character described including a pair of spaced standards, a drill supporting bar pivotally connected at one end to one of said standards adjacent its upper end, a work supporting member carried by said standards at their lower ends, said member comprising a pair of inwardly extending tubular rods mounted at their outer ends in said standards, the inner ends of said rods terminating in spaced relation 50 with each other, a central rod having its opposite ends mounted in the opposed ends of said tubular rods, means for detachably holding the opposite ends of said central rod within the opposing ends of said tubular rods, a depending drill carried by said supporting bar intermediate of its ends, and means for lowering said supporting bar to engage the drill with the work carried upon said supporting member. 55 60

In testimony whereof I hereunto affix my signature in the presence of two witnesses.

WILLIAM R. BOOTH.
